CLAUDE L. FRIEL, OF LOS ANGELES, CALIFORNIA, ASSIGNOR OF ONE-HALF TO
LEGRAND FRIEL, OF LOS ANGELES, CALIFORNIA.

MATRIX.

1,114,128.

Specification of Letters Patent.

Patented Oct. 20, 1914.

Application filed May 9, 1913. Serial No. 766,484.

To all whom it may concern:

Be it known that I, CLAUDE L. FRIEL, a citizen of the United States, residing at the city of Los Angeles, in the county of Los

5 Angeles and State of California, have invented new and useful Improvements in Matrices, of which the following is a specification.

10 My invention relates to polygonal matrices having four or more casting edges in which edges molds to form characters or forms are located which are used in line casting, and the object thereof is to provide matrices that are susceptible of being distributed into 15 magazines so that they will occupy the same position in the magazine as before each use thereof. I accomplish this object by the matrix described herein and illustrated in the accompanying drawings forming a part 20 of this application in which:

Figure 1 is a front elevation of my improved matrix. Fig. 2 is a top edge view. Fig. 3 is a bottom edge view of a matrix having molds for a combination of letters.

25 In the drawings I have illustrated what I term a square matrix having four casting edges and each edge having two characters or combinations of characters set reversely to each other. The reversed letter is at the 30 right of the other letter and for distinction will be called the bottom letter. Other polygonal forms of matrices may be used.

It so happens that in the use of four or more edged matrices with two letters in each edge 35 that one matrix will be used with a top letter and the next with a bottom letter, and such letters may be found on the top edge, or on the side edge, or on the bottom edge. It is necessary to the best use of my matrices 40 that each matrix shall on every occasion occupy the same relative position in the magazine and shall be capable of being distributed by mechanism after the line is cast so as to enter the magazine with the same edge at the 45 bottom thereof on every occasion of use and the same side or face always toward the operator. To accomplish this result I have designed mechanism for distributing the matrices to the magazine which will be described. 50 In an application hereafter to be filed. In order to render the matrices susceptible of such use the body 5 of each matrix is provided with a kerf 6 in one edge near the top and a notch 7 at the top of the other edge

and a central transverse hole 8 which is 55 preferably egg shaped. These central holes are so located that when the matrices are stacked together with the bottom edges on a level surface a line passing along the lower edge of each hole will be parallel with the 60 surface on which they rest. These holes are further located so that when the matrix is suspended on a rod it will turn thereon to bring the bottom of the matrix directly below the rod, that is to say the hole is eccentric 65 to the magnitude or weight of the matrix. This construction is necessary for the proper distribution of the matrix by the mechanism designed by me for that purpose. Matrix impressions or molds 9 are provided in each 70 casting edge and there are preferably two molds in each casting edge. When two are used they are set reversely to each other.

Having described my invention what I claim is:

1. A polygonal matrix having a central transverse hole, said hole being eccentric to the weight, said matrix having a plurality of casting edges, each casting edge having a different character.

2. A polygonal matrix having an egg shaped central transverse hole therein so located that the smaller end of the hole is nearest to the top edge of the matrix and the bottom portion of the matrix is the heaviest, 85 said matrix having different characters in each of its casting edges and each edge forming a casting edge.

3. A polygonal matrix having a kerf in one edge near the top and a notch at the top 90 of the other edge on the outer side thereof, said matrix having a central hole eccentric to its weight, and having a plurality of casting edges with different characters in each of said edges.

4. A polygonal matrix having a central transverse hole, the center of magnitude of which is eccentric to the center of gravity of the matrix, said matrix having a plurality of casting edges, each edge having a different 100 character.

In witness that I claim the foregoing I have hereunto subscribed my name this 1st day of May, 1913.

CLAUDE L. FRIEL.
